CLAIM

The ornamental design for an article of jewelry, as shown and described.

DESCRIPTION

FIG. 1 is a rear elevational view of the article of jewelry;

FIG. 2 is a right-side elevational view thereof;

FIG. 3 is a front elevational view thereof;

FIG. 4 is a front, right-side perspective view thereof;

FIG. 5 is a left-side elevational view thereof;

FIG. 6 is a top plan view thereof; and,

FIG. 7 is a bottom plan view thereof.

The broken lines depict portions of the article of jewelry that form no part of the claimed design.
